United States Patent

Des. 242,372
Patented Nov. 16, 1976

242,372

PRACTICE PUCK

Albert Marcucci, 1493 Kenmuir Ave.,
L5G 4B6 Mississauga, Ontario, Canada

Filed May 2, 1975, Ser. No. 573,841

Term of patent 14 years

Int. Cl. D21—02
U.S. Cl. D34—5 GP

FIG. 1

FIG. 2

FIG. 1 is a perspective view from above of a practice puck showing my design, the view from underneath being identical and the hidden portion in FIG. 1 being the same as the visible portion; and

FIG. 2 is a plan view thereof, the view from directly beneath being identical.

I claim:

The ornamental design for a practice puck, as shown and described.
